UNITED STATES PATENT OFFICE.

HEINRICH BOCKISCH, OF POUGHKEEPSIE, NEW YORK, ASSIGNOR TO M. WELTE & SONS OF NEW YORK, N. Y., A CORPORATION OF NEW YORK.

MECHANISM FOR SYNCHRONIZING THE OPERATIONS OF MOVING PARTS.

1,279,639.

Specification of Letters Patent. Patented Sept. 24, 1918.

Application filed April 20, 1916, Serial No. 92,388. Renewed December 20, 1917. Serial No. 208,149.

To all whom it may concern:

Be it known that I, HEINRICH BOCKISCH, a subject of the Emperor of Austria-Hungary, residing at Poughkeepsie, in the county 5 of Dutchess and State of New York, have invented certain new and useful Improvements in Mechanism for Synchronizing the Operations of Moving Parts, of which the following is a specification.

10 This invention has relation to mechanism for synchronizing the operations of moving parts. As the invention may be very desirably applied to synchronizing of a plurality of automatically operated musical instruments, respectively reproducing different parts of a musical composition, I have selected this particular application of the invention for illustration herein, and particularly have illustrated the preferred embodiment of the invention when it is to be employed as a means for synchronizing the operations of a phonograph—which for the purpose of the present invention is regarded as a species of musical instrument, although 15 its use is not restricted to the reproduction of musical compositions—and a pneumatically operable instrument of the style which utilizes a traveling perforated note sheet as the primary selecting element or record, 20 player pianos, automatic organs, and orchestrions forming well known examples of such pneumatically - operable instruments. In such case, the phonograph may reproduce the solo part of a musical composition and 25 the piano, organ, or orchestrion may reproduce the accompaniment, for example: The mechanism forming the present invention serving so to synchronize the operations of the phonograph and piano, organ or orchestrion that the accompaniment notes will be 30 sounded in proper relation to the solo notes. I would have it understood, however, that this particular application of the invention is merely exemplary, as it is not my purpose 35 in anywise to restrict the invention to the synchronizing of phonographs with other musical instruments, however important this particular application may be, because I recognize the fact that the invention may by 40 suitable modification be applied to many different classes of machinery or apparatus, the said modification having reference principally to the substitution for the herein illustrated “primary controlling elements,” 45 which are peculiarly appropriate to a phonograph and a self-playing piano, organ or orchestrion, of other primary controlling elements more especially adapted for the particular class or style of machines, apparatuses or instruments which are to be synchronized. 50

In the accompanying drawings, wherein like characters of reference denote corresponding parts in the several views:

Figure 1 is a schematic sectional representation of the preferred embodiment of my invention, illustrating, further certain elements of a phonograph and a self-playing piano, organ or the like to show its preferred application thereto. 65

Fig. 2 is a detail representation showing the primary controlling valves, the electric motors for controlling the same and certain adjunctive elements, the parts being shown in the position they occupy when the circuit to the motor G has been completed and before the circuit to the motor H has been closed. 70

Fig. 3 is a detail representation, partly diagrammatic, showing the means whereby the circuit to the motor H is closed, and also showing the secondary valves and the electric motor for controlling the air forces which operate the secondary valves, the secondary valves being shown in the position they assume when the conduit for regulated suction is in communication with the conduit for unregulated or stronger suction. 80

Fig. 4 is a detail representation of the chest which contains the releasing valve and the valves which control the circuits to the secondary valve-motors I and J, these several valves being desirably arranged in a chest having appropriate chambers for the valves and a common conduit for the valve chambers. The circuit controlling valves are in the position they occupy when the circuit to the motor I is closed and the circuit to the motor J is open. 90

Fig. 5 is a detail sectional view on the line 5—5 of Fig. 4 but showing the releasing valve in open position. 95

Fig. 6 is a detail sectional view on the line 6—6 of Fig. 4.

Fig. 7 is a detail sectional representation of the member which controls the releasing valve from the combined action of the primary controlling valves, showing the parts in the position they occupy when both primary controlling valves have been opened. 100

110

A and B designate two movable or traveling parts whose movements are to be synchronized by the present mechanism. In this particular application of the invention the 5 part A is the table of a phonograph of any approved or suitable kind and the part B is a perforated note sheet such as is commonly employed as the record for playing or controlling the playing or player pianos, piano 10 players, automatic organs, orchestrions and certain other musical instruments. It is well known that in practice the table A is rotated at a regulated speed by a suitable motor, and hence it is not necessary to illustrate or further refer herein to the mechanism 15 for driving said table. It is also understood that the note sheet or record B is caused in practice to travel at a regulated speed over a tracker board b, and that it is 20 perforated and in its travel over the tracker board opens and closes the mouths of ducts formed in the latter, these ducts respectively communicating with certain pneumatics of a player action whose nature is such that it 25 operates or controls the operation of the sound-emitting elements of the instrument. It is apparent that any means of a movable nature which is adapted to open and close the several ducts, in a predetermined succession, may be utilized in lieu of the perforated note sheet B, and hence I would 30 have it understood that the term "record" wherever herein used is intended to comprehend any such device or means. In fact, 35 I wish it understood at the outset that while I have illustrated and shall herein describe with particularity a very advantageous embodiment of my invention as well as a particular application thereof, it is nevertheless 40 to be understood that both said particular embodiment and application are merely exemplary, and that the invention may be otherwise and variously embodied and applied to the synchronizing of many different 45 kinds of instruments, apparatuses or machines without departing from its spirit or the scope of the subjoined claims.

The herein exemplified record B is wound onto a take-up roll c while playing the instrument, and this take-up roll derives motion from a wind motor, illustrated conventionally at C. As it is common in instruments of this class to connect such motors with the take-up roll c for the purpose 50 stated, and as a particular connection to the motor with such roll is in no wise a part of my present invention, I do not consider it essential to describe any particular connection.

55 In practice it is preferred to so arrange the synchronizing mechanism that the speed of one machine or instrument will be directed or controlled by the other, primarily. In other words, it is preferred to so arrange 60 the parts that the speed of one machine or

instrument will be increased or reduced whenever it falls behind or goes ahead of the other, the speed of the latter being unchanged by the synchronizing mechanism. When a phonograph is synchronized with a 70 player piano or the like it is preferable to control the speed of the piano or the like from the phonograph and the herein illustrated mechanism exemplifies such an arrangement.

Moving with the table A and selector B respectively are what are herein termed "primary controlling elements". These primary controlling elements control the operation of primary controlling valves D and E. 80 The primary controlling element associated with the table A and valve D is preferably an elongated member 10, of a material which forms a good conductor of electricity, which member may desirably be fixedly secured to the under side of the table and is suitably insulated therefrom. The primary controlling element for the selector B and valve E may desirably be an integral part of said selector, the latter being shown as having a 90 series of spaced apertures 11 disposed along its longitudinal edge. The bridging member 10 is preferably correlated with two spring contacts 12^a and 13^a in such manner as to bridge the space between the latter, intermittently. The contacts 12^a and 13^a are connected respectively with two conductors 12 and 13, one of which extends from a suitable source F of electrical energy of low voltage, and the other of which extends to 100 an electro-magnet G from which a bus bar 14 and return wire 14^a extend back to the source of energy. Hence when the contact bridging member 10 is engaged with the contacts 12^a and 13^a the magnet G will be 105 energized. The apertures 11 in the selector B are arranged intermittently to open special ducts 15 in the tracker board b, thereby setting into operation certain intermediate mechanism which closes the circuit through 110 an electro-magnet H. In this particular exemplification of the invention the duct 15 opens into a chamber 16 which is separated by a membrane 17 from a conduit 18 which in turn is in controllable communication 115 with a bellows 19 whose movable board is provided with a projection 19^a arranged to act when the bellows is collapsed, upon two contacts 20^a and 21^a which are connected with conductors 20 and 21, one of which— 120 20—extends from the source of energy F and the other of which—21—extends back to the positive terminal of the magnet H, which magnet has its negative terminal connected to the bus bar 14. The chamber 16 has communication with the conduit 18 through a bleed hole 16^a.

The membrane 17 is connected to the stem 22 of a valve 23 which is arranged in a chamber 24 having a port 25 opening into 130

the suction conduit 18 and a port 26 opening into the bellows 19. The valve 23 is arranged to cover and uncover the port 25 and hence to control communication of the suction conduit 18 with the bellows. The chamber 24 also has an atmospheric port 27 which is closed by the valve 23 when the latter is in the position in which the port 25 is uncovered and is opened when said valve is 10 in the position in which it closes the port 25.

In practice the bridging member 10 and apertures 11 are so correlated that the magnets G and H will be energized throughout the same length of time and with the same 15 length of intervals between the periods during which they are energized. In this exemplification of the invention, the bridging member 10 is of arcuate form and bridges the gap between the contacts 12^a and 13^a 20 throughout approximately one-half of each revolution of the table A: and the apertures 11 are of such length and are so spaced from each other that at the normal or intended speed of the selector B each opens the duct 25 15 for a length of time the same as that consumed by the table in making one-half of a revolution.

The primary control valves D and E are mounted in chambers 28 and 29 which have 30 ports 30 and 31 leading to a suction conduit 32, and said valves among other purposes serve to control communication of the said chambers with said suction conduit. These chambers 28 and 29 are also, preferably, 35 provided with ports 30^a and 31^a, through which they respectively may have communication with chambers 30^b and 31^b which are open to the atmosphere, as shown. In such case, the valves D and E are respectively arranged 40 to close the ports 30^a and 31^a when they have been moved to open the ports 30 and 31, and to open said ports 30^a and 31^a when they have been moved to close the ports 30 and 31. The ports 30^a and 31^a may, as 45 shown in Fig. 1, be provided with plugs 30^c and 31^c having openings of slightly larger diameter than the valve stems d and e which pass therethrough: or these plugs may be omitted as shown in Fig. 2. In either event, 50 the chambers 28 and 29 and the several chambers (hereinafter described) having communication therewith will be under suction when the valves D and E are moved to open communication of said chambers with 55 the conduit 32 and this suction will be more or less quickly replaced by air at atmospheric pressure—according to the sizes of the openings between the chambers 28 and 30^b and chambers 29 and 31^b—when the valves D, E 60 have been moved to uncover said openings and close the ports 30 and 31.

The wind motor C hereinbefore referred to is suitably connected, as by a duct 33^a for example, with a channel 33, the pressure in 65 which is variably controlled through mech-

anisms which are, respectively, in turn controlled by the valves D and E, said mechanisms including parts which have communication with the chambers 28 and 29, and being of a nature such that they assure the 70 utmost accuracy and certainty in the synchronization of the moving parts.

It may be here mentioned that, in the present exemplification of the invention, the valves D and E open at the same instant and 75 close at the same instant when the parts are moving in proper synchronism. At this time, the wind motor is under weak or regulated suction, from a suitable source having communication with the channel 33 through 80 a duct 33^b. This may be referred to as a normal condition. When, however, the valve D is opened before the valve E, the speed of the wind motors should be increased and this increase is brought about in the 85 present exemplification of the invention by opening communication of the channel 33 with a suitable source of strong or unregulated suction through a duct 34 which has controllable communication with such 90 source. On the other hand, when the valve E is opened before the valve D the speed of the wind motor should be decreased, and this is effected in the herein exemplified 95 form of the invention by opening the channel 33 to the atmosphere through a port 35, which has controllable communication with the atmosphere. In this exemplification of the invention the duct 34 extends from a chamber 36 having a port 37 leading to the 100 suction conduit 18 which contains unregulated strong suctional force, and said chamber 36 has a secondary controlling valve 38 which is operated automatically, by means hereinafter set forth, to open said port and consequently bring about a further attenuation of the air in the channel 33. In order that the opening through the duct 34 may be 105 variably regulated, I prefer to provide it with an adjustable restricting device, which device may consist of a stem 39 threaded into a block 40 and extending into the 110 duct 34.

The means herein exemplified for opening the port 35 to the atmosphere, includes a 115 valve 41 arranged in a channel 42 having an atmospheric duct 43, the said valve being carried by a membrane 44 and normally pressed to close the port 35 by a spring 45. The atmospheric duct 43 may be provided 120 with a regulating device, as screw valve 41^b, for example. The membrane 44 separates the chamber 42 from a second chamber, 46, which is connected to a duct 47 leading from a chamber 48. This chamber 48 has a port 49 through which it may communicate with the suction conduit 18 and also has a port 50 through which it may have communication with the atmosphere. A secondary controlling valve 51 is mounted in this chamber 130

and is movable automatically to open the port 49 and close the port 50 or to open the port 50 and close the port 49.

The secondary controlling valves 38 and 51 are connected, respectively, to stems 52 and 53 which in turn are connected to membranes 54 and 55. These membranes separate the suction conduit 18 from chambers 56 and 57. The chamber 56 is provided with a duct 58 and the chamber 57 is provided with a duct 59. The mouths of these ducts are opened and closed severally by valves 60 and 61, carried or formed by, the armatures of electro-magnets I and J, respectively. Hence when the magnet I is energized it will attract its armature and open the duct 58 to the atmosphere, whereupon the membrane 54 will be moved to move the valve 38 and uncover the port 37. Similarly when the magnet J is energized it will attract its armature and open the duct 59, thus admitting atmospheric air to the chamber 57 and causing the valve 51 to move and open the port 49. The chambers 56 and 57 are connected with the suction conduit 18 by bleed holes 56^a and 57^a so that the valves 38 and 51 are promptly returned to their former positions when the magnets I and J are deenergized. In order to provide guidance for the stem 52 and at the same time prevent any leakage around the stem which would reduce the suction in conduit 33 when valve 38 is closed, said stem 52 extends through a guiding member 52^a, the opening in which is covered by a flexible air tight pulpette or apron 52^b of approximately inverted cup-shape, whose edge is secured in an air tight manner to said member, the pulpette being also connected, at its center, in an air tight manner, to a nut 52^c which moves with the stem 52, and being adapted to move with the stem without destroying its function of preventing leakage around the stem.

The energizing of these magnets I and J is controlled from the primary controlling valves D and E, respectively, the following instrumentalities being exemplified for this purpose, to wit:—

The valve D has its stem *d* connected at its opposite ends to membranes 62 and 63 and the valve E similarly has opposite ends of its stem *e* connected to membranes 64 and 65. The membrane 62 separates the suction conduit 32 from a chamber 66 and the membrane 64 separates the suction conduit 32 from a chamber 67. Ducts 68 and 69 enter these chambers 66 and 67, respectively, and have their mouths arranged to be covered and uncovered by armatures *g* and *h* of the magnets G and H, respectively, or by valves carried by said armatures. When the magnets are energized they attract their armatures and thus open the respective ducts 68 and 69 to the atmosphere so that air at atmospheric pressure enters the chambers 66

and 67 respectively, whereupon the valves D and E are moved to uncover the ports 30 and 31. The membrane 63 is arranged between the hereinbefore referred to chamber 30^b and a chamber 70, and the membrane 65 similarly is arranged between the hereinbefore referred to chambers 31^b and a chamber 71. The chambers have communication with the chambers 28 and 29 respectively, through channels 72 and 73. Hence when the chambers 28 and 29 are under suction the chambers 70 and 71 similarly will be under suction, whereby the valves D and E will be locked or maintained effectively in open position. The chambers 70 and 71 have atmospheric ports 72^a and 73^a. These ports are closed and opened by spring pressed valves 74 and 75 carried by membranes 76 and 77 which are mounted in chambers 78 and 79 having atmospheric ports 80 and 81 on the valve sides of the membranes. On the opposite sides of said membranes are ducts 84 and 85 extending from a chamber 126 which contains a releasing valve 130 hereinafter set forth.

K and L designate two valve units or members which respectively are interposed in the connections between the primary controlling valve chambers 28 and 29 and control the energizing and deenergizing of the magnets I and J, through intermediate mechanism hereinafter described, the said members or units K and L being in turn controlled from the primary controlling valves D and E and releasing valve 130 with whose chambers they are connected.

Referring to these members K and L, it will be noted that the member K has a duct 86 which extends from the chamber 28 and enters a chamber 87 having a membrane 88 which separates the chamber 87 from an atmospheric channel 89, and also has two chambers 90 and 91 connected with the channel 89 by ports 92 and 93, respectively. The port 92 has one of its walls pierced by one end of a channel 94 whose other end enters the chamber 91. The member K also has a chamber 95 provided with a duct 96 which leads to the chamber 126 of the releasing valve 130. The port is tapped by a duct 97 which leads to a chamber 157 for a purpose hereinafter particularly set forth. The chamber 95 is separated from the atmospheric channel 89 by a membrane 98. The membranes 88 and 98 are connected respectively to valve stems 99 and 100. The stem 99 carries valves 101 and 102 which are so arranged that when the stem is in one position the valve 101 will open the port 92 to the chamber 90 and the valve 102 will close said port 92 against the channel 89, and when the stem is in its other position the valve 101 will close said port 92 against the chamber 90 and will open it to said channel 89. The stem 100 similarly is provided with

two valves, marked 103 and 104, so arranged thereon that in one position of the stem the port 93 will be open to the chamber 91 and closed to the channel 89 and in the other 5 position of the stem said port 93 will be closed to the chamber 91 and opened to the channel 89.

Preferably the stems 99 and 100 are connected to springs 99^a and 100^a for pressing 10 them into the positions in which the valves 102 and 104 close the ports 92 and 93 against entrance of atmospheric air from the channel 89. The chamber 90 is connected by a duct 105 with the chamber 29 containing the 15 valve E.

The corresponding unit or member, L, is of construction similar to that of the member or unit K and need not be particularly described. Its parts are numbered as follows:—106, atmospheric channel: 107 and 108, chambers separated from the atmospheric channel by membranes 109 and 110: 20 111 and 112, other chambers, separated from the atmospheric channel 106 by ports 113 and 114: 115, channel leading from port 113 to chamber 112: 116, valve stem having valves 117 and 118 and pressed by spring 116^a: 119, stem carrying valves 120 and 121 and pressed by a spring 119^a. It will be 25 noted that the chamber 107, which corresponds to the chamber 87 of the unit K, is connected with the chamber 29 by a duct 122 and that the chamber 111, which corresponds to the chamber 90 of the unit K, is 30 connected with the chamber 28 by a duct 123. It will also be noted that the chamber 108, which corresponds to the chamber 95 of the unit K, is connected by a duct 124 with the releasing valve chamber 126 to 35 40 which the duct 96 leading from said chamber 95 is connected, and further it will be noted that the port 114, which corresponds to the port 93 of the unit or member K, is connected through a duct 125 with a chamber 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

is a valve 140 which controls the operation of the releasing valve 130 and, in turn, is controlled by the primary controlling valves D and E. The valve 140 has a stem 141 which is connected to a membrane 142 and a 70 spring 143. The tendency of the spring is to cause the valve 140 to close the port 139. This valve is mounted in a chamber 144 having a port 145 connected by a duct 145^a with a bleed hole 145^b entering the suction conduit 128. The chamber 144 also has communication with a channel 146 whose mouth is closed by a valve 147 which valve is carried by a membrane 148 and is pressed to its seat over the mouth of the channel by a 80 spring 149. This channel 146 conducts atmospheric air to the chamber 144, the said air entering through a duct 150 into a chamber 151 between the membrane 148 and channel 146. The valve 140 alternately closes the 85 ports 139 and 145. The membrane 142, to which the stem of the valve 140 is secured, is arranged between two chambers, marked 152 and 153 respectively, the former of which contains air at atmospheric pressure 90 and the other of which is connected with the chamber 29 (containing the primary controlling valve E) by a duct 154. The membrane 148 similarly separates the atmospheric chamber 151 from a chamber 155 95 and the said chamber 155 is connected with the chamber 28 (containing the primary controlling valve D) by a duct 156. The stem 141 extends through a guiding element 141^a having a leak proof pulpette 141^b around the 100 stem, such as hereinbefore described.

Reference has heretofore been made to the fact that the duct 97 leading from the port 93 of the unit or member K extends to a chamber 157 and that the corresponding duct 125 of the unit or member L extends to a chamber 158. These chambers 157 and 158 are provided with membranes 159 and 160 and the said membranes are connected to the stems 161 and 162 of the valves 163 110 and 164. These valves are mounted in chambers 165 and 166. The chamber 165 has a port 167 through which it may have communication with the suction conduit 128 and also has a port 168 through which it may 115 have communication with the atmosphere, and the valve 163 is arranged to close these ports alternately. Similarly the chamber 166 has a port 169 through which it may have communication with said suction conduit 128 and a port 170 through which it may have communication with the atmosphere and these ports are closed alternately by the valve 164. Moreover, these chambers have passages 171 and 172 which extend to 120 pneumatics 173 and 174 respectively. The movable boards of these pneumatics carry elements 175 and 176 arranged to bridge gaps, indicated at 177 and 178, between contact elements 181, 182 and 184, 185 of an 130

The chamber 126 of the releasing valve 130 has a port 127 through which it has communication with a suction conduit 128 50 and also has a port 129 through which it has communication with the atmosphere. Its valve 130 is movable to open these ports alternately. This valve is provided with a stem 131 whose opposite ends are attached 55 to membranes 132 and 133. The membrane 132 separates the suction conduit 128 from a chamber 134 which chamber has communication with the suction conduit through a bleed hole 135. The membrane 133 is arranged in a chamber 136 which has communication with the chamber 126 through a passage 137.

The chamber 134 is provided with a duct 138 which extends from a port 139. Arranged 60 in operative relation with said port

electrical circuit and said members 175 and 176 are of a nature such that they will conduct the current from one contact element to the other. The circuit just referred to 5 includes a bus bar 179 to one end of which a wire 180 extends from the positive pole of the source of electrical energy F. To this bus bar is connected the contact element 181 operatively associated with which is a second 10 contact element 182, these two contact elements being spaced as indicated at 177. From the contact element 182 a wire 183 extends to the terminal 183^a of the electro-magnet J. The contact element 184 also is 15 connected to the bus bar 179 and from its end is spaced, as indicated at 178, the contact element 185 from which a wire 186 extends to the terminal 186^a of the electro-magnet I. Other terminals of these electro-magnets I 20 and J are connected to a bus bar 187 from which a wire 188 leads to the bus bar 14, the latter being connected with the negative terminal of the source of electrical energy by the wire 14^a hereinbefore referred to. Accordingly 25 it will be seen that when the pneumatic 173 is collapsed the circuit is closed through the electro-magnet J and when the pneumatic 174 is collapsed the circuit is closed through the electro-magnet I.

30 Extending from the chamber 136 of the releasing valve mechanism is an atmospheric duct 189. This duct is opened and closed by a pneumatic 190 whose movable board is provided with a valve 191. This pneumatic 35 is controlled by an electro-magnet M whose operation, in turn, is controlled by the primary valves D and E. The armature 192 of the magnet M is arranged to close an atmospheric duct 194 when the armature is 40 in one position and to open said atmospheric duct when the armature is in the other position—that is to say to close the duct when the magnet is deenergized and to open the duct when the magnet is energized. This duct opens into a chamber 195 which is 45 separated by a membrane 196 from a suction conduit 197. The suction conduit 197 has a passage 198 which leads to the atmosphere and a passage 198^a which extends to the interior of the pneumatic 190. The membrane 196 is connected to a stem 199 which carries two valves marked 200 and 201 respectively. These valves are so arranged that the passage 198 is in communication 50 either with the suction conduit 197 or with the atmosphere according to whether the chamber 195 is open to the atmosphere or closed against the atmosphere. In other words, when the magnet M is energized and 55 the duct 194 is thus opened to the atmosphere the membrane 196 is moved to cause the valve 200 to cut off communication between the suction conduit 197 and the passage 199 and the valve 201 is moved to open the passage 199 to the atmosphere. This 60

65

results in the expansion of the pneumatic 190 and movement of the valve 191 to open position and thus places the chamber 136 under atmospheric pressure. When, however, the magnet M is deenergized and the 70 duct 194 closed, the valves 200 and 201 are in the positions wherein the passage 198 is open to the suction conduit and is closed against the atmosphere. In the latter case the pneumatic 190 is collapsed and the valve 75 191 closes the duct 189.

The magnet M is energized and deenergized under control of the primary valves D and E, as already stated, as follows: The chambers 28 and 29 containing these valves 80 are provided with channels 202 and 203 which respectively lead to the interior of pneumatics 204 and 205. These pneumatics are provided with members 206 and 207 which are arranged to bridge gaps, indicated at 208 and 209, in a conducting wire 210 which extends from the positive terminal of the source of electrical energy F to the positive terminal 210^a of the magnet M. From the negative terminal 211^a of this 90 magnet M a wire 211 extends back to the negative terminal of the source of electrical energy F.

It will be seen that in the operation of the mechanism the magnets G and H are 95 intermittently energized, the energizing of the magnet G being brought about by the closing of the circuit through the wires 12, 13, bus bar 14 and wire 14^a when the element 10 bridges the gap between the contacts 100 12^a and 13^a, and the energizing of the magnet H being brought about by the supply of atmospheric air to the chamber 16, which occurs whenever the duct 15 is opened to the atmosphere and which results in the opening 105 of the port 25 and the consequent opening of the way to the bellows 19 from the suction channel 18, this in turn resulting in the collapsing of said bellows and the closing of the circuit thereby through the contacts 20^a, 110 21^a, wires 20, 21, magnet H, bus bar 14 and wire 14^a.

When the magnet G is energized, atmospheric air is admitted to the chamber 66 and the primary controlling valve D is thus 115 caused to uncover the port 30 and cover the atmospheric port 30^a, whereupon the chamber 28 is put under suction from the channel 32. Similarly, when the magnet H is energized, atmospheric air is admitted to the chamber 67 and the primary controlling valve E is moved to uncover the port 31 and cover the port 31^a, so that the chamber 29 is under suction from said channel 32. As already stated when both valves D and E 120 open simultaneously the two instruments are working in synchronism and no change in the relative speed should take place. It also has been previously stated herein that 125 when the valve D opens first the speed of the 130

- wind motor C is increased and when valve E opens first the speed of the wind motor is reduced, by subjecting the regulated wind channel 33 to strengthened suctional impulses or to weakened suctional impulses, so to speak, until the record B and table A are traveling at their synchronized speed. There are several things however, which have been considered in the production of the herein disclosed mechanism for the purpose here in view. Among other things it should be noted that if the record B is traveling faster than the table A its synchronizing aperture 11 will have passed the tracker board while the bridging element 10 is still in engagement with the contacts 12^a and 13^a and consequently while the port 30 is still open. On the other hand, when a synchronizing aperture 11 comes into registration with the duct 15 after the bridging element 10 has engaged the contacts 12^a and 13^a, it will be in registration with said duct after said contact bridging element 10 has passed out of engagement with said contacts and consequently the port 31 will be open when the port 30 has been closed. The synchronizing mechanism accordingly is so constructed that it is influenced only by the beginning of the aperture 11 and the beginning of the contact. Tracing the operation in detail it will be found to be as follows:
- Assuming now that the circuit through the magnet G has been closed before the circuit through the magnet H: the valve D is raised and the chamber 28 is placed under suction. This suction is communicated to the chamber 70 so that the membrane 63 connected to the stem d of the valve D is under suction from said chamber, thus locking the valve in its open position. At the same time the chamber 87 in the unit or member K is placed under suction, which acting upon the membrane 88 moves the valves 101 and 102 to open communication of the channel 94 with the atmospheric conduit 89. Air at atmospheric pressure accordingly flows from the channel 89 into the chamber 91 and thence through port 93 and duct 97 thereby subjecting the side of the membrane 159 which is in the chamber 157 to atmospheric pressure. The valve 163 is now held in the position in which it closes the suction port 167 and opens the atmospheric port. The chamber 55 being now under atmospheric pressure, which is communicated to the bellows 173 through the channel 171, the circuit to the magnet J is interrupted. This is a preparatory function.
- At the same time the chamber 155 of the section or member which controls the releasing valve 130 is placed under suction from the chamber 28 through the duct 156, which acting upon the membrane 148 in said chamber opens the valve 147 carried by the mem-

brane and allows atmospheric air to enter the chamber 144 which contains the secondary control valve 140 for releasing valve 130. This atmospheric air replaces the suction which this chamber was formerly subjected to through the bleed duct 145^a and bleed hole 145^b from the conduit 128. This also is a preparatory function.

At the same time, the chamber 158 is placed under suction from the chamber 28 as the way is open through the duct 123, chamber 111, port 113, channel 115, chamber 112, port 114, and duct 125. The chamber 158 at the upper side of the membrane 160 being under suction while atmospheric pressure is exerted against the lower side of said membrane, it follows that the valve 164 will be raised. This results in the uncovering of the suctional port 169 and the opening of the way to the bellows 174 from the suction conduit 128, through the chamber 166 and channel 172, the atmospheric port 170 to the chamber 166 being closed at the same time. The bellows 174 hence is collapsed and its contact bridging member 176 is brought into engagement with the contacts 184 and 185, which closes the circuit to the magnet I. This magnet being now energized, attracts its armature 60 and opens the duct 58 to the atmosphere. Air at atmospheric pressure now enters the chamber 56, causing the secondary valve 38 to uncover the port 37, whereupon the suction conduit 18 is in communication with the suction conduit 33 through port 37, chamber 36 and duct 34. This is the effective function causing the wind motor to run faster.

At the same time, the bellows 204 is placed under suction from the chamber 28 through the channel 202. This bellows, being collapsed, interrupts the circuit through the wire 210 by moving contact bridging element 206, which bridged the space 208 in said wire, and hence the magnet M is de-energized. This de-energizing of the magnet M acts through its armature 192 to close the duct 194. The membrane 196 at this time is in a position wherein the valve 201 closes the channel 198 against the atmosphere and the valve 200 opens said channel to suction from the suction conduit 197. The bellows 190 accordingly is under suction and the valve 191 carried by said bellows closes the duct 189.

Recapitulating, we find the parts in the following condition: the valve D is raised and locked: membrane chamber 157 is being supplied with air at atmospheric pressure and the valve 163 cannot be raised: valve chamber 144 is in communication with the atmosphere but its port 139 is closed by the valve 140 against the passage of this air: the wind motor conduit 33 has been supplied suddenly with more suction by the opening of the valve 38: magnet M has been de-energized

and in consequence duct 189 has been closed against the atmosphere. This is the condition of the synchronizing mechanism before the synchronizing aperture 11 of the music roll opens the duct 15. Now when the synchronizing aperture 11 is in registration with the duct 15 the following occurs:

Air at atmospheric pressure enters the chamber 16 through the duct 15, whereupon the valve 23 is moved to uncover the suction port 25 and close the atmospheric port 27, and the bellows 19 is collapsed. This causes the closing of the circuit through the magnet H and this in turn opens chamber 67 to the atmosphere and causes the valve E to uncover the port 31 and cover the port 31^a, whereupon the chamber 29 is put under suction from the conduit 32. From this chamber 29 the following chambers are placed under suction, to wit: chamber 71 through channel 73, chamber 107 through duct 122, chamber 90 through duct 105 and chamber 153 through duct 154 the effects of which are as follows:

The chamber 107 being now under suction, membrane 106 and valve stem 116 will be raised, thus causing the valves 118 and 117 respectively to close the passage 115 against the suction from the chamber 111 and open it to the atmospheric conduit 106. Atmospheric air now passes from conduit 106, through port 113, passage 115, chamber 112, port 114, and duct 125 and into the chamber 158. This atmospheric air, replacing the suction which was formerly in said chamber 158, causes the valve 164 to move and close the suction port 169 and open the atmospheric port 170. Chamber 166 now contains air at atmospheric pressure and this flows to the bellows 174 through the passage 172. This bellows accordingly is expanded thus interrupting the circuit through the magnet I whereupon the valve 38 is moved to close the suction port 37 and the supply of additional suction to conduit 33 immediately ceases.

Simultaneously with the foregoing, chamber 153 and chamber 90 are placed under suction from the chamber 29, through the ducts 154 and 105, respectively.

The placing of the chamber 153 under suction causes the secondary release-control valve 140 to be moved and uncover the port 139 so that the atmospheric air in the chamber 144 (it will be remembered that channel 146 was opened to the atmosphere when the valve D was moved to uncover the port 30) may flow through the duct 138 to the chamber 134. See Fig. 7. Consequently the release valve 130 will be moved to uncover the port 127 thereby opening the chamber 126 to the suction conduit 128. The valve 130 will be maintained in this position by the suction communicated to the chamber 136

through the channel 137 until the duct 189 is opened to the atmosphere.

The chamber 90 of the unit K is now under suction, as stated, but communication of said chamber with the channel 94 has been closed by the suctional force communicated to the chamber 87 when the valve D was moved to open the chamber 28 to the suction conduit 32.

The valve E being in the position in which it opens the port 31 so that the chamber 29 is under suction, the bellows 205 is collapsed, thus further interrupting the already interrupted circuit to the magnet M.

Recapitulating these functions resulting directly from the opening of the port 31 by the movement of the valve E we find (1) the supply of additional suction to the wind motor conduit 33 through the duct 34, ceased; (2) the release valve 130 was moved to place its chamber 126 under suction, and (3) an additional break or interruption was introduced into the circuit to the magnet M.

Now, as the chamber 126 is connected with the chambers 95 and 108 of the units or members K and L by ducts 96 and 124 respectively, and with the chambers 78 and 79 by ducts 84 and 85, respectively, the following results will be noted:

(1) The chamber 95 is placed under suction through duct 96 and the valves 103 and 104 accordingly are caused to move to close the communication between the channel 94 and the duct 97 and to open communication between the atmospheric conduit 89 and the duct 97. Accordingly air at atmospheric pressure now enters the chamber 157 from the chamber 89 directly by way of the port 93 and duct 97, instead of by way of the port 92, channel 94, chamber 91, port 93 and duct 97. This is an effective precautionary function, it being remembered that the valves 101 and 102 are held in position to cut off communication of suction chamber 90 with the channel 94 under control of the suction entering the chamber 87 from the chamber 28 when the valve D is raised, and as said valve is raised before the valve E it may fall before said valve E and in such case valves 101 and 102 also may fall and allow suctional force to enter the chamber 157 while the valve E is raised, unless the way is closed. Hence by closing the way to suction and opening it to atmosphere the after ends of the contacts and apertures 11 are neutral and only the beginnings are an operation and the operation of the mechanism is not disarranged by the closing of the valve D.

(2) The chamber 108 being under suction the valves 120 and 121 are moved to cut off communication of duct 125 with chamber 112 and open said duct to atmospheric conduit 106 through port 114. This also is a pre-

cautionary function analogous to that just described.

(3) The chambers 78 and 79 being under suction through the ducts 84 and 85, the 5 membrane valves 74 and 75 are raised and atmospheric air is permitted to enter the chambers 70 and 71 through the ports 72 and 73.

It will now be noted that among other things the suctional force locking the valves 10 D and E has been released, the releasing valve 130 having placed several chambers in condition, as to air pressures, which assure the return of the valves when chambers 66 and 67 are cut off from communication 15 with the atmosphere and that this occurred as soon as the primary controlling valve last opened, E in this instance, was opened. Care should be taken that said releasing valve 130 be also in condition as to pressures 20 that it may be closed when and only when both the magnets G and H are deenergized, thereby restoring all the parts to the condition wherein they are ready for repetition of the foregoing operations. This is assured 25 by the opening of the duct 189 to the atmosphere. It will be remembered that this duct, which leads to the chamber 136 having membrane 133 connected to the stem of the valve 130, is cut off from the atmosphere 30 when the bellows 190 is collapsed and that this bellows is collapsed when the magnet M is deenergized and that the magnet M is deenergized when either bellows 204 or 205 is collapsed. In consequence it will follow that 35 it is only when both bellows 204 and 205 are expanded, (it will be remembered that both are collapsed when both magnets G and H are energized) that the circuit to the magnet M is closed. The closing of the circuit 40 through the magnet M results in the opening of the chamber 195 to the atmosphere which in turn causes the valves 200 and 201 to fall, thereby opening channel 198 to the atmosphere and permitting air at atmospheric pressure to enter the bellows 190 and expand the latter, thus opening the duct 45 189 and through said duct 189 communicating atmospheric pressure to the membrane 133. This causes the valve 130 promptly to 50 return to the position in which it cuts off communication between the chamber 126 and the suction conduit 128 and opens communication between said chamber and the atmosphere through the port 129. 55 The parts are now in their original positions and if the wind motor is still lagging behind, the operations hereinbefore recited are repeated and they are repeated at very short intervals, determined by the speed of 60 the table A, until the table A and record B are traveling in synchronism with each other.

If the record B is traveling faster than the table A, then the operations hereinbefore recited will be reversed: *i. e.* magnet H will

be energized first, valve E will be raised 65 first, membrane 159 will be subjected to suction before the membrane 160, the valve 163 will be raised before the valve 164, the circuit through the magnet J will be closed before the circuit through the magnet I, 70 and the suction conduit 33 hence will be opened to the atmosphere thereby slowing down the motor. The valve E is now slowing the speed of the motor and preparing the parts for the functions of the valve D as 75 will be understood.

When the circuit through both magnets G and H are closed at the same moment and the table A and motor C are working in synchronism the speed of neither should be 80 changed, and they are not changed as will now be seen.

Magnets G and H being energized at the same moment, the valves D and E rising exactly at the same time, suction is communicated simultaneously to membrane chambers 87 and 107 locking the passageways to membrane chambers 157 and 158. In consequence neither magnet I nor J can be energized as contact bellows 173 and 174 90 will not be influenced and neither valve 38 nor valve 51 will influence air conduit 33.

It of course will be understood that the records are prepared with reference to each other and when one of the records is a phonograph record it should have means of some appropriate nature for indicating or determining the position in which it is laid upon the phonograph table. Again it will be understood that both instruments should 95 be started at the same time and at the same speed. When one of the instruments to be synchronized is a phonograph it will be desirable, though not essential, to provide means whereby the table will be started at 100 the full speed or will quickly attain such full speed. For the latter purpose it may be given an additional starting impulse by hand or by mechanism, which ever is preferred.

While I have herein illustrated and described the invention as embodied to utilize air at atmospheric and less than atmospheric pressures, it will be understood that it will not be a departure from the spirit of the invention as defined by the appended claims to utilize air at other relatively different pressures, as at atmospheric pressure and above atmospheric pressure, for example.

Having now described the invention and 120 set forth in detail the preferred embodiment and application thereof, what I believe to be new and desire to secure by Letters Patent is:—

1. Mechanism for synchronizing the operations of moving parts, comprising, in combination, a motor for one of said parts, a plurality of primary controlling valves,

and means between the valves and motor for increasing or decreasing the speed of the latter according to which of said valves is opened first, including connections whereby 5 either valve when opened first performs its function of increasing or decreasing the speed of the motor and either valve when opened second causes the effect of the opening of the first opened valve upon the motor 10 to cease.

2. Mechanism for synchronizing the operations of moving parts, comprising, in combination, a motor for one of said parts, a plurality of primary controlling valves 15 respectively controlled by the parts to be synchronized, and connections between the primary valves and said motor, said connections including movable elements for the primary valves respectively and means 20 whereby the movement of either of the primary valves when opened first moves the corresponding element in one direction to affect the speed of the motor and the movement of the other primary valve moves said 25 element in the other direction to terminate such effect.

3. Mechanism for synchronizing the operations of moving parts, comprising, in combination, a motor for one of said parts, a plurality of primary controlling valves, a 30 plurality of secondary controlling valves, connections between the secondary valves and the motor, and operative connections between the primary valves and the secondary 35 valves, the latter connections including means whereby the opening of either primary valve causes the corresponding secondary valve to become operative with respect to the motor and maintains the other 40 of said valves in position in which it is inoperative with respect to the motor.

4. Mechanism for synchronizing the operations of moving parts, comprising, in combination, a motor for one of said parts, 45 primary controlling valves, secondary controlling valves, connections between the secondary valves and the motor, and operative connections between the primary valves and the secondary valves, respectively, the latter 50 connections including means whereby said secondary valves will be actuated respectively to increase or decrease the speed of the motor, according to which of the primary controlling valves is opened first, and the 55 opening of either primary controlling valve will maintain the non-actuated secondary valve in position in which it is inoperative upon the motor and will also cause the effect of the opening of the first opened primary 60 valve upon its secondary valve to cease when the other of the primary controlling valve is opened.

5. Mechanism for synchronizing the operations of moving parts, comprising, in 65 combination, a motor for one of said parts, a

plurality of primary controlling valves, means for periodically opening said valves from the moving parts, a plurality of secondary controlling valves, connections between the primary valves and the secondary valves 70 respectively and between the secondary valves and the motor whereby the speed of the motor is increased when one of the primary valves is opened first and decreased when the other primary valve is opened first, the 75 connections between the primary valves and the secondary valves including means whereby when either of the primary valves is opened it opens the corresponding secondary valve and when the other of said primary valves is opened it closes said secondary valve.

6. Mechanism for synchronizing the operations of moving parts, comprising, in combination, a motor for one of said parts, 80 a plurality of primary controlling valves, means for periodically opening said valves from the moving parts, a plurality of secondary controlling valves, connections between the primary valves and the secondary valves 85 respectively and between the secondary valves and the motor whereby the speed of the motor is increased when one of the primary valves is opened first and decreased when the other primary valve is opened first, the connections between the primary valves and the secondary valves including means whereby when either of the primary valves is opened it opens the corresponding secondary valve and when the other of said 90 primary valves is opened it closes said secondary valve, and said connections further including means for maintaining the other of said secondary valves closed until its corresponding primary valve is opened first. 105

7. Mechanism for synchronizing the operations of moving parts, comprising, in combination, a pneumatic motor for one of the parts to be controlled, a plurality of primary controlling valves periodically actuated under the influence of the parts to be controlled, a plurality of secondary controlling valves the movement of one of which increases the speed of the motor and the movement of the other decreases the 110 speed of the motor, a plurality of actuating mechanisms for said secondary valves, intermediate controlling valves for said actuating mechanisms and means for opening one of the intermediate controlling valves 115 when one of the primary controlling valves is opened and for closing the said intermediate controlling valve when the other of said primary valves is opened.

8. Mechanism for synchronizing the operations of moving parts, comprising, in combination, a plurality of primary controlling valves, chambers in which said valves operate and locking means for the valves, said locking means including mem- 125 130

branes operable to hold said valves in open position, chambers by which said membranes are covered and means for establishing communication between the valve 5 chambers and the membrane chambers.

9. Mechanism for synchronizing the operations of moving parts, comprising, in combination, a motor for one of said parts, a pair of primary controlling valves, means 10 for opening the primary controlling valves severally under control of said moving parts respectively, means between the primary controlling valves and the motor for increasing or decreasing the effective strength 15 of the forces exerted upon the motor according to whether the one or the other of said valves is opened first, means for locking the valves in open position, and means whereby both valves are released under control 20 of the valve last opened.

10. Mechanism for synchronizing the operations of moving parts, comprising, in combination, a motor for one of said parts, a pair of primary controlling valves, means 25 for opening the primary controlling valves severally under control of said moving parts respectively, means between the primary controlling valves and the motor for increasing or decreasing the effective strength of 30 the forces exerted upon the motor according to whether the one or the other of said valves is opened first, means including a releasing valve for locking the primary valves in open position, and means whereby the 35 releasing valve is operated under control of the primary valve last opened.

11. Mechanism for synchronizing the operations of moving parts, comprising, in combination, a motor for one of said parts, a pair of primary controlling valves, means 40 for opening the primary controlling valves severally under control of said moving parts respectively, means between the primary controlling valves and the motor for increasing or decreasing the effective strength 45 of the forces exerted upon the motor, according to whether the one or the other of said valves is opened first, means for locking the valves in open position, and means 50 including a releasing valve, whereby both primary controlling valves are released under control of the one last opened, means for locking the releasing valve, and means controlled by the primary controlling valves 55 for releasing the releasing valve.

12. Mechanism for synchronizing the operations of moving parts, comprising, in combination, a motor for one of said parts, a pair of primary controlling valves, means 60 for opening the primary controlling valves severally under control of said moving parts respectively, means between the primary controlling valves and the motor for increasing or decreasing the effective strength 65 of the forces exerted upon the motor, means

for locking the valves in open position, a releasing valve, connections between the releasing valve and the locking means, the said connections being controlled by the releasing valve, and means whereby the releasing valve is actuated under control of the primary controlling valves. 70

13. Mechanism for synchronizing the operations of moving parts, comprising, in combination, a motor for one of said parts, a pair of primary controlling valves, means 75 for opening the primary controlling valves severally under control of said moving parts respectively, means between the primary controlling valves and the motor for increasing or decreasing the effective strength 80 of the forces exerted upon the motor, means for locking the valves in open position, a releasing valve, connections between the releasing valve and the locking means, and 85 connections between the releasing valve and the primary controlling valves, the last named connections including a member which is operated to open the releasing valve when both primary controlling valves 90 have been opened.

14. Mechanism for synchronizing the operations of moving parts, comprising, in combination, a plurality of primary controlling valves, means controlled by the moving parts for opening said valves respectively, means for locking the primary controlling valves in open position, a releasing valve, connections between the releasing valve and the locking means, and connections between the releasing valve and the primary controlling valves, including a member having connection with the releasing valve and separate connections to the primary controlling valves and which member closes the connections to the releasing valve when only one of the primary controlling valves is open and is operated to open said connections to the releasing valve when both of the primary controlling valves 100 are open. 105

15. Mechanism for synchronizing the operations of moving parts, comprising, in combination, a plurality of primary controlling valves, means controlled by the moving parts for opening said valves respectively, means for locking the primary controlling valves in open position, a releasing valve, connections between the releasing valve and the locking means, and connections between the releasing valve and the primary controlling valves, including a member having connection with the releasing valve and separate connections to the primary controlling valves and which member closes the connection to the releasing valve when only one of the primary controlling valves is open and is operated to open said connection to the releasing valve when both of the primary controlling valves 110 115 120 125 130

- are open, means for locking the releasing valve in open position, and means for releasing the last named locking means, including connections controlled by the primary valves, the last named connections being interrupted when either primary valve is open and operatively established when both are closed. 65
- 5 16. Mechanism for synchronizing the operations of moving parts, comprising, in combination, a plurality of primary controlling valves, means controlled by the moving parts for opening said valves respectively, means for locking the primary controlling valves in open position, a releasing valve, connections between the releasing valve and the locking means, and connections between the primary controlling valves and the releasing valve, the latter 70 connections including a valve, means whereby the opening of one primary controlling valve admits fluid to one side of the valve of the connection and means whereby the opening of the other primary controlling 75 valve opens the valve of the connection and permits said fluid to pass to actuate the releasing valve. 75
- 10 17. Mechanism for synchronizing the operations of moving parts, comprising, in combination, a plurality of primary controlling valves, means controlled by the moving parts for opening said valves respectively, means for locking the primary controlling valves in open position, a releasing valve, connections between the releasing valve and the locking means, and connections between the primary controlling valves and the releasing valve, the latter connections including a valved duct, connections whereby 80 the valve of said duct is controlled by one primary controlling valve, means through which fluid is admitted to the duct when its valve is opened, a second duct, a valve between said ducts and means whereby the latter valve is opened under control of the other primary controlling valve. 85
- 15 18. Mechanism for synchronizing the operations of moving parts, comprising, in combination, a plurality of primary controlling valves, means controlled by the moving parts for actuating said valves respectively, means for locking the primary controlling valves in open position, a releasing valve, connections between the releasing valve and the locking means whereby the latter is controlled from the former and connections between the releasing valve and the primary controlling valves, said connections including a channel open to the atmosphere and a plurality of valves in said channel controlled respectively by the primary controlling valves. 90
- 20 19. Mechanism for synchronizing the operations of moving parts, comprising, in combination, a plurality of primary controlling valves, means controlled by the moving parts for opening said valves respectively, means for locking the primary controlling valves in open position, a releasing valve and a valved connection between the releasing valve and the primary controlling valves, 95 said connection including means controlled by one of the primary controlling valves for establishing communication of a part of the connection with the atmosphere and also including means controlled by the other primary valve, whereby the valve of the connection is moved to permit atmospheric air to pass to actuate the releasing valve. 100
- 25 20. Mechanism for synchronizing the operations of moving parts, comprising, in combination, a pneumatic motor for one of said parts, a plurality of primary controlling valves, a plurality of secondary controlling valves, operative connections between the primary controlling valves and the secondary controlling valves, respectively, a conduit having communication with the motor, and connections between said secondary valves and the conduit, the latter connections including a port through which the conduit is opened to the atmosphere when one of the secondary valves is opened. 105
- 30 21. Mechanism for synchronizing the operations of moving parts, comprising, in combination, a pneumatic motor for one of said parts, a conduit having communication with the motor, a connection for regulated wind to said conduit, a conduit for unregulated wind connections between the two conduits, a valve in said connections and means controlled by predetermined variations in the relative speeds of the parts to be synchronized for operating said valve. 110
- 35 22. Mechanism for synchronizing the operations of moving parts, comprising, in combination, a pneumatic motor for one of said parts, a conduit having communication with the motor a connection for regulated wind to the conduit, a connection for unregulated wind to the conduit, the conduit also having an atmospheric port, and means operable in accord with the parts to be synchronized for controlling said port and the connection for unregulated wind. 115
- 40 23. Mechanism for synchronizing the operations of moving parts, comprising, in combination, a pneumatic motor for one of said parts, a conduit having communication with the motor, a connection for regulated wind to said conduit, said conduit being also provided with a suction duct and an atmospheric port, a conduit for unregulated wind, having connection with said duct, secondary controlling valves for controlling the suction duct and atmospheric port, respectively, primary controlling valves for controlling the secondary valves, respectively, and operative connections between the parts to be synchronized. 120
- 45 125

chronized and the primary controlling valves for operating the latter in accord with said parts.

24. Mechanism for synchronizing the operations of moving parts, comprising, in combination, a pneumatic motor for one of said parts, a conduit having communication with the motor, a connection for regulated wind to said conduit, said conduit being also provided with a suction duct and an atmospheric port, a conduit for unregulated wind having connection with said duct, secondary controlling valves for controlling the suction duct and atmospheric port, respectively, primary controlling valves, and connections between the primary controlling valves and the secondary valves whereby each of the secondary valves is opened when the corresponding primary valves is opened and is closed when the other primary valve is opened.

25. Mechanism for synchronizing the operation of moving parts, comprising, in combination, a pneumatic motor for one of said parts, primary controlling valves, and means for increasing or decreasing the effective strength of the pneumatic forces exerted upon the motor according to which of said valves is actuated first, said means including additional valves, a connection between one additional valve and a primary valve, through which said additional valve is operated, a connection between the said additional valve and the other primary valve, the latter connection being controlled by the additional valve, and corresponding connections between the other additional valve and said primary valves.

26. Mechanism for synchronizing the operations of moving parts, comprising, in combination, a pneumatic motor for one of said parts, primary controlling valves and their chambers, secondary controlling valves, connections between the secondary valves and the motor and connections between the primary valve chambers and the secondary valves, the last named connections including additional valves, the parts of the connections between the primary valve chambers and the additional valves being so arranged that one additional valve is controlled by one primary valve and controls communication of the other primary valve with one secondary valve and the other additional valve is controlled by the last mentioned primary valve and controls communication of the other primary valve with the other secondary valve.

27. Mechanism for synchronizing the operations of moving parts, comprising, in combination, a pneumatic motor for one of said parts, means for increasing or decreasing the effective strength of the forces exerted upon the motor, the said means includ-

ing a plurality of movable elements for controlling the increase and decrease respectively, a plurality of primary controlling valves, and connections between said primary controlling valves and elements respectively, each of said connections including a plurality of additional valves, one valve in each connection serving when open to cause movement of its corresponding movable element and the other valve in each connection serving when open to cause said movable element to be locked against movement.

28. Mechanism for synchronizing the operations of moving parts, comprising, in combination, a pneumatic motor for one of said parts, means for increasing or decreasing the effective strength of the forces exerted upon the motor, the said means including a plurality of movable elements for controlling the increase and decrease respectively, a plurality of primary controlling valves, and connections between said primary controlling valves and elements respectively, each of said connections including a plurality of additional valves, one valve in each connection serving when open to cause movement of its corresponding movable element and the other valve in each connection serving when open to cause said movable element to be locked against movement, the connection also including means whereby the additional valves which perform the aforesaid locking function are controlled from the primary valves.

29. Mechanism for synchronizing the operations of moving parts, comprising, in combination, a pneumatic motor for one of said parts, means for increasing or decreasing the effective strength of the forces exerted upon the motor, the said means including a plurality of secondary valves, a plurality of movable members which control said valves, respectively, a plurality of primary controlling valves, and connections between said primary controlling valves and movable members respectively, each of said connections including a plurality of additional valves, one valve in each connection serving when open to cause movement of its corresponding movable member and the other valve in each connection serving when open to cause said movable member to be locked against movement.

30. Mechanism for synchronizing the operations of moving parts, comprising, in combination, a motor for one of said parts, a plurality of primary controlling valves, connections between the primary controlling valves and the motor, the said connections including movable elements and additional valves, the said additional valves when open causing the movable elements to be locked against movement, and means under the

combined control of the primary valves for opening said additional valves.

31. Mechanism for synchronizing the operations of moving parts, comprising, in combination, a pneumatic motor for one of said parts, means for increasing or decreasing the effective strength of the forces exerted upon the motor, the said means including a plurality of movable elements for controlling the increase and decrease respectively, a plurality of primary controlling valves, and connections between said primary controlling valves and elements respectively, each of said connections including a plurality of additional valves, one valve in each connection serving when open to cause movement of its corresponding movable element and the other valve in each connection serving when open to cause said movable element to be locked against movement and means under the combined control of the primary valves for controlling the additional valves which performs the aforesaid locking function.
32. Mechanism for synchronizing the operations of moving parts, comprising in combination, a motor for one of said parts, a plurality of primary controlling valves, connections between the primary valves and the motor, the said connections including movable elements and additional valves, the said additional valves when opened causing the movable elements to be locked against movement, means for locking the primary valves in open position, a releasing means for the locking means, means for controlling the releasing means from the primary valves and a connection between the releasing means and the additional valves whereby said additional valves are opened when the releasing means is actuated.

33. Mechanism for synchronizing the operations of moving parts, comprising, in combination, a motor for one of said parts, a plurality of primary controlling valves, means for opening the primary controlling valves severally under control of said moving parts respectively, connections between the primary controlling valves and the motor, means for locking the valves in open position, a releasing means for said locking means, and means whereby the releasing means are controlled by the combined action of the primary controlling valves.

34. Mechanism for synchronizing the operations of moving parts, comprising, in combination, a motor for one of said parts, a plurality of primary controlling valves, means for opening the primary controlling valves severally under control of said moving parts respectively, connections between the primary controlling valves and the motor, means for locking the valves in open position, releasing means for said locking

means, locking means for the releasing means and releasing means for the last named locking means all controlled by the primary controlling valves.

35. Mechanism for synchronizing the operations of moving parts, comprising, in combination, a motor for one of the parts, means through which power is communicated to said motor, primary controlling elements operatively related with the moving parts respectively, electric circuits periodically closed by said primary controlling elements respectively, and means for increasing or decreasing on the motor the strength of the power communicated to said motor, according to whether the one or the other of said circuits is first completed.

36. Mechanism for synchronizing the operations of moving parts, comprising, in combination, a pneumatic motor for one of said parts, primary controlling valves for controlling the pneumatic forces to the motor and means for electrically controlling the operations of said valves, said means including electric circuits, means for closing each of said circuits in a timed relationship with the movements of the moving parts, means controlled by the circuits for operating the primary controlling valves respectively, and means whereby the primary controlling valves effect an increase or decrease of the effective strength of the pneumatic forces exerted upon said motor, according to which of the valves is first operated.

37. Mechanism for synchronizing the operations of moving parts, comprising, in combination, a motor for one of the parts to be synchronized, a plurality of controlling valves, means between said valves and said motor for varying the relative speed of said parts under control of said valves, said last named means including means whereby when one of said valves is opened it performs its function and when the other of said valves is opened the effect of the first named valve upon the motor ceases, moving elements traveling in related cycles in accord with the parts to be synchronized, electric controlling means for said valves, and means for energizing said electric controlling means once in each cycle of operation of said moving elements.

38. Mechanism for synchronizing the operations of moving parts, comprising, in combination, a pneumatic motor for one of the parts, a plurality of pneumatically operable primary valves, connections between the valves and the motor operable to increase and decrease the speed of the motor under control of said valves respectively, and means for operating said valves in accord with the movements of the moving parts respectively, the said means including ducts, connections between the ducts

and the valves, electric circuits, primary controlling elements for controlling the circuits, and means in said circuits for controlling said ducts.

- 5 39. Mechanism for synchronizing the operations of moving parts, comprising, in combination, a pneumatic motor for one of the parts, a plurality of primary valves having connection with the motor and controlling the speed thereof, and means for operating said valves under control of the parts to be synchronized, said means including electric circuits, a primary controlling element movable in accord with one of said parts for closing one of the circuits, a primary controlling element movable in accord with the other of said parts, and pneumatically operable means for closing the other circuit under control of the last 20 named controlling element.

40. Mechanism for synchronizing the operations of moving parts, comprising, in combination, a motor for one of said parts, a plurality of periodically actuated primary controlling valves, operative connections between the primary controlling valves and the motor, primary controlling elements operatively related with the moving parts, respectively, electric circuits periodically closed by said primary controlling elements, respectively, means in said circuits for opening the primary controlling valves, respectively, means for locking the valves in open position, and means operable to release the 35 valves when both of said circuits have been closed.

41. Mechanism for synchronizing the operations of moving parts, comprising, in combination, a pneumatic motor for one of said parts, a plurality of primary controlling valves means between the primary controlling valves and the motor for increasing and decreasing the effective strength of the pneumatic forces exerted upon the motor 45 under control of said valves, electric circuits, means for controlling the circuits in accord with the movements of said moving parts respectively, means controlled by said circuits for opening the valves respectively, 50 means for locking the valves in open position and means for releasing the valves.

42. Mechanism for synchronizing the operations of moving parts, comprising, in combination, a pneumatic motor for one of said parts, a plurality of primary controlling valves, means between the primary controlling valves and the motor for increasing or decreasing the effective strength of the pneumatic forces exerted upon the motor 55 according to whether the one or the other of said valves is actuated first, electric circuits, means for controlling the circuits in accord with the movements of said moving parts, respectively, means controlled by said 60 circuits for opening the valves respectively,

means for pneumatically locking the valves in open position, and means for releasing both valves upon the opening of the one last opened.

43. Mechanism for synchronizing the operations of moving parts, comprising, in combination, a plurality of primary controlling valves, operative connections between said valves and the moving parts respectively, whereby the valves are opened 70 in accord with the movements of said parts, means for varying the relative speeds of the parts under control of said valves, means for locking the valves in open position, a releasing means for said valves, a locking means for the releasing means, means including an electric circuit for releasing the last named locking means and means whereby said circuit is controlled from the primary valves. 80

44. Mechanism for synchronizing the operations of moving parts, comprising, in combination, a plurality of primary controlling valves, operative connections between said valves and the moving parts, respectively, whereby the valves are opened in accord with the movements of said parts, means for varying the relative speeds of the parts under control of said valves, means for locking the valves in open position, a releasing means for said valves, a locking means for the releasing means, and a releasing means for the last named locking means, including an electric circuit and means whereby the latter circuit is interrupted when 100 either primary valve is open.

45. Mechanism for synchronizing the operations of moving parts, comprising, in combination, a plurality of primary controlling valves, operative connection between 105 said valves and the moving parts, respectively, whereby the valves are opened in accord with the movements of said parts, means for varying the relative speeds of the parts under control of said valves, means for pneumatically locking the valves in open position, a releasing valve, connections between the releasing valve and the locking means, connections between the releasing valves and the primary controlling valves whereby the 110 releasing valve is controlled by the latter, a locking means for the releasing valve and a releasing means for the last named locking means including a valve, an electric circuit for controlling the operation of the latter 115 valve and means whereby said circuit is controlled from the primary controlling valves. 120

46. Mechanism for synchronizing the operations of moving parts, comprising, in combination, a plurality of primary controlling valves, means between the primary controlling valves and the motor for varying the relative speeds of the parts under control of the primary controlling valves, electric circuits, means for controlling the 125 130

- circuits in accord with the movements of the moving parts, respectively, means controlled by said circuits for opening the valves, respectively, means for pneumatically locking 5 the valves in open position, a releasing valve, connections between the releasing valve and the locking means, connections between the releasing valve and the primary controlling valves whereby the releasing valve is operated under control of the primary controlling valve last opened, a locking means for the releasing valve, and a releasing means for the last named locking means, including a valve, an electric circuit for controlling the 10 operation of the latter valve and means whereby the latter circuit is interrupted when either primary controlling valve is open.
47. Mechanism for synchronizing the operations of moving parts, comprising, in combination, a motor for one of said parts, a plurality of primary controlling valves, a secondary controlling valve having connection with the motor, means connecting both 15 primary valves with the secondary valve, said means including an electric circuit, and means whereby the circuit is closed under control of one primary valve and opened under control of the other primary valve.
48. Mechanism for synchronizing the operations of moving parts, comprising, in combination, a motor for one of said parts, a plurality of primary controlling valves, a plurality of secondary controlling valves 20 having connection with the motor, and connections including electric circuits between the primary controlling valves and the secondary valves, respectively, through which the secondary valves are opened when the corresponding primary valves are opened, said connections including means whereby the second opened primary valves closes the secondary valve which was opened by the first opened primary valve.
49. Mechanism for synchronizing the operations of moving parts, comprising, in combination, a motor for one of said parts, primary controlling valves, secondary controlling valves, electric circuits, means controlled by the moving parts for controlling said circuits respectively, means controlled by the circuits for opening the primary valves, respectively, other circuits, means controlled by the latter circuits for opening 25 the secondary valves respectively, and means for making and breaking the latter circuits under control of the respective primary valves.
50. Mechanism for synchronizing the operations of moving parts, comprising, in combination, a pneumatic motor for one of said parts, primary controlling valves, secondary controlling valves, electric circuits, means controlled by the moving parts for controlling said circuits, respectively, means 30
- controlled by the circuits for opening the primary valves, respectively, other circuits, means controlled by the latter circuits for opening the secondary valves respectively, and means for pneumatically making and breaking the latter circuits under control of the respective primary valves. 70
51. Mechanism for synchronizing the operations of moving parts, comprising, in combination, a pneumatic motor for one of said parts, a pair of secondary valves for controlling the effective strength of the pneumatic forces exerted upon the motor, electrical controlling means for the secondary valves, a pair of primary controlling 75 valves actuated periodically under the control of the moving parts, means for energizing the electrical controlling means of one of the secondary valves when one of the primary controlling valves is opened and means for deenergizing said electrical controlling means when the other of said primary controlling valves is opened. 80
52. Mechanism for synchronizing the operations of moving parts, comprising, in combination, a pneumatic motor for one of said parts, a pair of secondary valves for controlling the effective strength of the pneumatic forces exerted upon the motor, electrical controlling means for the secondary valves, a pair of primary controlling 85 valves actuated periodically under the control of the moving parts, means for energizing the electrical controlling means of one of the secondary valves when one of the primary controlling valves is opened and means for deenergizing said electrical controlling means when the other of said primary controlling valves is opened. 90
53. Mechanism for synchronizing the operations of moving parts, comprising, in combination, a pneumatic motor for one of said parts, a conduit for regulated wind having connection with the motor, a suction duct and an atmospheric port connected to said 95 conduit, a plurality of primary valves, means including electric circuits for opening said valves severally and periodically under control of the parts to be synchronized respectively, and means through which the primary valves respectively control said duct and port. 100
54. Mechanism for synchronizing the operations of moving parts, comprising, in combination, a pneumatic motor for one of said parts, a conduit for regulated wind having connection with the motor, a suction duct and an atmospheric port connected to said 115 conduit, a plurality of primary valves, means including electric circuits for opening said valves severally and periodically under control of the parts to be synchronized respectively, and means through which the primary valves respectively control said duct and port. 120
55. Mechanism for synchronizing the operations of moving parts, comprising, in combination, a pneumatic motor for one of said parts, primary controlling valves, secondary controlling valves, electric circuits, means controlled by the moving parts for controlling said circuits, respectively, means 125

valves severally and periodically under control of the parts to be synchronized respectively, secondary valves operatively related to said duct and port for controlling the 5 same respectively and means for connecting the primary valves with the secondary valves respectively.

55. Mechanism for synchronizing the operations of moving parts, comprising, in 10 combination, a pneumatic motor for one of said parts, a conduit for regulated wind having connection with the motor, a suction duct and an atmospheric port connected to said conduit, secondary controlling valves for 15 controlling said duct and port respectively, electrical controlling means for the secondary valves, circuits in which said electrical controlling means are included, circuit making and breaking elements in said circuits, 20 a pair of primary controlling valves controlling the circuit making and breaking elements and means for actuating the primary controlling valves under the control of the parts to be synchronized.
- 25 56. Mechanism for synchronizing the operations of moving parts, comprising, in combination, a motor for one of said parts, a plurality of primary controlling valves, connections between the primary controlling 30 valves and the motor for increasing or decreasing the effective strength of the forces exerted upon the motor, said connections including electric circuits, a circuit making and breaking element in each of the circuits 35 and a movable member controlling the passage of air to each circuit making and breaking element, said connections further including additional valves which when opened cause the said movable members to be locked 40 against movement.

57. Mechanism for synchronizing the operations of moving parts, comprising, in combination, a motor for one of said parts, a plurality of primary controlling valves, 45 connections between the primary controlling valves and the motor for increasing or decreasing the effective strength of the forces exerted upon the motor, each of said connections including an electric circuit, a pneumatically operable circuit making and breaking element in said circuit, a movable member for controlling the passage of air to said circuit making and breaking element, a duct having connection with said member, 50 55 an additional valve and means whereby when said valve is open said movable member is locked against movement.

58. Mechanism for synchronizing the operations of moving parts, comprising, in 60 combination, a motor for one of said parts, a plurality of primary controlling valves, connections between the primary controlling valves and the motor for increasing or decreasing the effective strength of the forces 65 exerted upon the motor, each of said connec-

tions including an electric circuit, a pneumatically operable circuit making and breaking element in each circuit, a movable member for controlling the passage of air to each circuit making and breaking element, and 70 ducts having connections with said members and with the primary controlling valves whereby one or the other of said circuits is completed according to which of the primary valves is actuated first.

59. Mechanism for synchronizing the operations of moving parts, comprising, in combination, a motor for one of said parts, primary controlling valves and connections between the primary controlling valves and 80 motor, said connections including secondary controlling elements, additional valves, a connection between one additional valve and a primary valve through which said additional valve is operated, a connection between 85 the said additional valve and the other primary valve, the latter connection being controlled by the additional valve, corresponding connections between the other additional valves and primary valves, electrical circuits 90 for controlling the secondary controlling elements, respectively, said circuits including make and break elements, and means controlled by the additional valves for controlling said make and break elements, re- 95 spectively.

60. Mechanism for synchronizing the operations of moving parts, comprising, in combination, a motor for one of said parts, primary controlling valves and connections 100 between the primary controlling valves and motor, said connections including secondary controlling elements, pneumatically operable additional valves, a connection between one additional valve and a primary valve 105 through which said additional valve is operated, a connection between the said additional valve and the other primary valve, the latter connection being controlled by the additional valve, corresponding connections 110 between the other additional valve and the primary valves, electrical circuits for controlling the secondary controlling elements, respectively, pneumatically operable make and break elements controlling said circuits, 115 and pneumatic ducts controlled by the additional valves and controlling said make and break elements.

61. Mechanism for synchronizing the operations of moving parts, comprising, in 120 combination, a motor for one of said parts, primary controlling valves, and connections between the primary controlling valves and the motor, said connections including secondary controlling elements, a plurality of 125 members, each having a plurality of passages for air of different pressures and a port connecting its passages and movable means operable to control communication between the said port and passages, a con- 130

nection between said movable means of one member and one of the primary valves through which the movable member is operated, a connection between the other 5 primary valve and one of the passages of said member, corresponding connections between the primary valves and the movable means and passage, respectively, of the other member, electric circuits through 10 which the secondary controlling elements are controlled, respectively, circuit making and breaking elements for controlling said circuits, respectively, and connections between said ports and the circuit making and 15 breaking means, respectively, for controlling the latter from the former.

62. Mechanism for synchronizing the operations of moving parts, comprising, in combination, a motor for one of said parts, 20 primary controlling valves, and connections between the primary controlling valves and motor, said connections including secondary controlling elements, a plurality of members, each having a plurality of passages for 25 air of different pressures and a port connecting its passages with each other, each member also having pneumatically operable valves connected to move in unison and controlling communication of the port with said 30 passages, respectively, a connection between the valves of one member and one of the primary valves through which the former are operated, a connection between said member and the other primary valve, one 35 valve of said member controlling communication, the latter connection and the port in said member, corresponding connections between the other member and the primary valves, electrical circuits for controlling the secondary controlling elements, 40 respectively, pneumatically operable make and break elements controlling said circuits, ducts communicating with the ports in said members and through which the make and 45 break elements respectively are controlled.

63. In a synchronizing mechanism, the combination of a motor for one of the parts to be synchronized, electric circuits, means controlled by said circuits for controlling 50 the forces which operate the motor, pneumatically operable circuit making and breaking elements in said circuits, valves, means through which the valves are operated in accord with the movements of 55 the parts to be synchronized, and pneumatic connections controlled by the valves for operating the circuit making and breaking elements.

64. In a synchronizing mechanism, the 60 combination of a motor for one of the parts to be synchronized, electric circuits, means controlled by said circuits for controlling the forces which operate the motor, pneumatically operable circuits making and 65 breaking elements in said circuits, and

means for controlling the pneumatic forces which operate said circuit making and breaking elements, the latter means including primary valves, means for operating said valves in accord with the movements 70 of the parts to be synchronized respectively, other valves, pneumatic connections between the latter valves and the circuit making and breaking elements respectively, and means for operating said latter valves under 75 control of the primary valves.

65. In a synchronizing mechanism, the combination of a motor for one of the parts to be synchronized, electric circuits, means controlled by said circuits for controlling 80 the forces which operate the motor, pneumatically operable circuit making and breaking elements in said circuits, and means for controlling the pneumatic forces which operate said circuit making and 85 breaking elements, the latter means including primary valves, means for operating said valves in accord with the movements of the parts to be synchronized respectively, other valves, pneumatic connections between 90 the latter valves and the circuit making and breaking elements respectively, and means for operating said latter valves under control of the primary valves, the last named means including operating members 95 for said other valves, pneumatic connections between the primary valves and the operating members, and additional valves in said connections, one of said additional valves being controlled by one primary valve and 100 controlling the pneumatic force from the other primary valve to one of said operating members and the other of said additional valves being controlled by said other primary valve and controlling the pneumatic force from the first mentioned primary valve to the other operating member. 105

66. In a synchronizing mechanism, the combination of a motor for one of the parts to be synchronized, electric circuits, means 110 controlled by said circuits for controlling the forces which operate the motor, pneumatically operable circuit making and breaking elements in said circuits, and means for controlling the pneumatic forces which operate said circuit making and breaking elements, the latter means including primary valves, means for operating said valves in accord with the movements of the parts to be synchronized respectively, other valves, 115 pneumatic connections between the latter valves and the circuit making and breaking element respectively, and means for operating said latter valves under control of the primary valves, said latter means including additional valves, connections between the additional valves and said other valves, means for moving the additional valves to such position that when one of the primary valves is opened pneumatic forces are per- 120 125 130

mitted to pass through said connections to operate one of the said other valves, and means for moving said additional valve under control of the other primary valve to 5 cut off the passage of said pneumatic forces when the latter primary valve is opened.

67. In a synchronizing mechanism, the combination of a motor for one of the parts to be synchronized, a pair of primary controlling valves, means for actuating said valves periodically and severally in accord with the parts to be synchronized respectively, a pair of pneumatically operable secondary controlling valves, connections between the secondary valves and the motor, through which the speed of the motor is increased and decreased under control of said valves respectively, motors for controlling the pneumatic forces which operate the 20 secondary valves, circuits in which said motors are located, circuit making and breaking elements in said circuits, valves intermediate the primary and secondary valves and controlling said circuit making and 25 breaking elements, and means whereby each of the intermediate valves is moved in one direction under control of one of the primary valves and is moved in the opposite direction under the control of the other primary valve.

68. In a synchronizing mechanism, the combination of a motor for one of the parts to be synchronized, a pair of primary controlling valves, means for actuating said valves periodically and severally in accord with the parts to be synchronized respectively, an air conduit, valve chambers in which the primary valves move, said chambers having communication with the air conduit when the valves are opened, a pair of double valves each of which is actuated under the control of one of the primary controlling valves and controls the pneumatic force from the chamber of the other of the 45 primary controlling valves, intermediate valves actuated by such controlled pneumatic force, a pair of electric circuits, circuit making and breaking means located in said circuit and controlled by the intermediate 50 valves, a pair of secondary valves, means in said circuits for controlling the secondary valves, and connections through which the speed of the motor is increased or decreased under control of the secondary valves respectively.

69. Mechanism for synchronizing the operations of moving parts, comprising, in combination, a motor for one of said parts, a pair of primary controlling valves, a pair 60 of additional valves, connections between the additional valves and the motor for effecting an increase or decrease of the speed of the motor respectively, a connection between one of the primary valves and one of the additional valves through which said additional

valve is actuated when the primary valve is opened, a connection leading from the other primary valve to the last named additional valve, said additional valve controlling the forces which pass through said connection, corresponding connections between the primary valves and the other additional valve, said additional valves acting when operated under control of the primary valves as aforesaid to prevent the passage of forces 70 through the connections controlled thereby so that when the primary valves open together both of the additional valves are closed to prevent either the increase or decrease of the speed of the motor.

70. Mechanism for synchronizing the operations of moving parts, comprising, in combination, a motor for one of said parts, electric motors, means whereby the electric motors effect an increase or decrease of the 85 speed of the first-named motor, respectively, circuits for the electric motors, circuit making and breaking means in said circuits respectively, and connections between the circuit making and breaking means and the 90 parts to be synchronized for controlling the circuit making and breaking means from said parts respectively, said means including parts which when operated separately effect the actuation of one or the other of the 95 circuit making and breaking means, and when operated in unison prevent the actuation of either circuit making and breaking means.

71. In a means for synchronizing the operations of moving parts, one of said parts having a rotatable member, a segmental contact bridging element on said rotatable member, an electric circuit having contacts which are intermittently bridged by said element, 100 a motor for the other moving part, a second electric circuit, means for closing the latter circuit under control of the other moving part to be synchronized, and means controlled by said circuits for accelerating and 105 diminishing the speed of the motor.

72. In a means for synchronizing the operations of moving parts, a motor for one of the parts, primary controlling elements movable in accord with the parts to be synchronized, circuits controlled by the primary controlling elements, and means controlled by said circuits for changing the speed of the motor, the means for completing the circuit from one primary controlling element including spaced apertures, a duct which is intermittently opened by said apertures, a pneumatic, connections between the pneumatic and duct whereby the pneumatic is operated under control of the spaced apertures and a circuit closing element carried by the pneumatic.

73. In a means for synchronizing the operations of moving parts, a pneumatic motor for one of the parts, a conduit having 130

- communication with the motor, a connection for regulated wind pressure to said conduit, other connections to said conduit through which it has communication with air of different strengths, respectively, valves controlling the latter connections, and means operated in accord with the moving parts respectively for controlling said valves.
- 10 74. In a means for synchronizing the operations of moving parts, a pneumatic motor for one of the parts, a conduit having communication with the motor, a connection for regulated wind pressure to said conduit, other connections to said conduit through which it has communication with air of different strengths, respectively, valves controlling the latter connections, means operated in accord with the moving parts, re-

spectively for controlling said valves, and 20 adjustable regulating valves in said connections.

75. In a means for synchronizing the operations of moving parts, a pneumatic motor for one of the parts, a suctional conduit 25 having communication with the motor, a connection for regulated suction to said conduit, the conduit also having an atmospheric port, a pneumatically operable valve for said port, a conduit for stronger or unregulated suction, a valved connection between the two conduits, a valved connection from the conduit for unregulated suction to the valve of the atmospheric port, and means for operating the valves of said connections under control of the parts to be synchronized.

In testimony whereof I affix my signature.

HEINRICH BOCKISCH.
